Patented Nov. 14, 1967

209,218

AN AMUSEMENT-TYPE INDICATOR

Mel Appel, Livingston, and Martin Schnur, West Orange, N.J., assignors to Elpo Industries Inc., Fair Lawn, N.J., a corporation of New Jersey

Filed Feb. 8, 1967, Ser. No. 5,719

Term of patent 14 years

(Cl. D34—5)

FIG. 1

FIG. 2

FIG. 3

FIG. 4

FIG. 5

We claim:

The ornamental design for an amusement-type indicator, as shown and described.
